Primary Examiner — Clare Ann Gannon(74) Attorney, Agent, or Firm — ArentFox Schiff LLP(57) CLAIM

The ornamental design for a sneaker as shown and described.

DESCRIPTION

FIG. 1 is perspective view of a first embodiment of a sneaker showing our new design;

FIG. 2 is front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is perspective view of a second embodiment of a sneaker showing our new design;

FIG. 9 is front view of the design shown in FIG. 8;

FIG. 10 is a rear view of the design shown in FIG. 8;

FIG. 11 is a left side view of the design shown in FIG. 8;

FIG. 12 is a right side view of the design shown in FIG. 8;

FIG. 13 is a top view of the design shown in FIG. 8; and,

FIG. 14 is a bottom view of the design shown in FIG. 8.

FIGS. 8-14 include broken lines for the purpose of illustrating environmental structure of the sneaker and forming no part of the claimed design. Moreover, the material shading shown in FIGS. 8-14 represents a knitted textile that forms part of the claimed design.
